UNITED STATES PATENT OFFICE.

JOSEPH H. SHEARN, OF LEEDS, MASSACHUSETTS, ASSIGNOR TO NONOTUCK SILK COMPANY, OF FLORENCE, MASSACHUSETTS, A CORPORATION OF MASSACHUSETTS.

SPOOL-HOLDER.

1,147,694.

Specification of Letters Patent. Patented July 20, 1915.

Application filed July 3, 1914. Serial No. 848,798.

To all whom it may concern:

Be it known that I, JOSEPH H. SHEARN, a citizen of the United States of America, residing in Leeds, in the county of Hampshire 5 and State of Massachusetts, have invented certain new and useful Improvements in Spool-Holders, of which the following is a specification.

This invention relates to spool holders.

10 An object of the invention is to provide a convenient and improved means for supporting a group of spools of thread.

Another object is to provide a device of 15 the class described which is arranged for convenient use.

A further object is to provide a holder for a group of spools so arranged that a portion of the thread on each spool and one 20 end face of the spool are visible to the operator.

Other objects will appear in the detailed 25 description to follow.

In general, my device comprises in one preferred form a body member provided 30 with a series of holes, horizontally disposed therein and adapted to receive the spools. A series of vertical slits, tangentially arranged with respect to said holes communicate between the holes and the lower face 35 of the body member and afford a means for leading the thread from the body. A pivoted bar member is adapted to close off a very small portion of each of said holes to retain the spools in position therein. A second bar member in parallel relation with 40 and secured to the first bar member is adapted to close the ends of all of the tangential slits. This second bar member not only confines the threads within the slits but forms a smooth rounded guide which prevents the threads from catching on the edges of the slits.

My device forms a simple and inexpensive 45 means for supporting a number of spools. It is particularly adapted for use by tailors and dressmakers and forms a convenient holder for any desired number of spools. The thread on spools arranged in my container is kept clean and cannot become snarled or tangled. Thus, it is an economical device and saves waste of thread. Furthermore, the thread spools are so supported and arranged that a portion of the thread is visible as well as the color number 50 on the end face of the spool. Thus the op-

erator can see at a glance the color and kind of thread on each spool.

A preferred embodiment of my invention is illustrated in the accompanying drawings 60 in which—

Figure 1 is a top plan view of my spool holder; Fig. 2 is a front elevational view thereof; Fig. 3 is an end elevational view; and Fig. 4 is a sectional elevational view 65 taken on the line 4-4 of Fig. 3 and looking in the direction of the arrows.

Referring to the drawings, *a* represents the body portion of the spool holder made of wood or any other suitable material. This member *a* is adapted to be secured to a 70 table in a convenient position by the arms *m*.

Disposed within the body *a* is a series of horizontal holes *b* which extend from the front face of the body *a* backwardly toward but not through the rear face thereof. The 75 holes *b* are arranged in a horizontal row and in parallel relation one with another. These holes *b* are adapted to receive spools *l* which are freely rotatable therein but are restrained from longitudinal movement by 80 means to be described. The top face of the body *a* is provided with a curved channel *h*, longitudinally disposed. This channel *h* is so arranged that the intersection thereof with the holes *b* forms apertures *i* through 85 which the color and quality of the thread is clearly visible. It is also to be noted that practically the entire end face of each spool *l* is visible which allows the operator to see the number thereon as indicated in Fig. 2. 90 This number usually indicates the exact shade of the thread on the spool.

Pivoted mounted in the member *a* at *d* is a depending bar *c* and secured thereto and in parallel relation therewith is a second bar member *e*. The member *c* is adapted when in the position shown in Fig. 1 to close off a very small portion of the holes *b* thereby restraining the spools *l* from longitudinal movement in said holes. The second bar *e* is adapted to swing in under the bottom face of the body *a* and to be removably secured thereto by a spring catch *f* as clearly shown in Fig. 3. Both bars *c* and *e* can be 95 swung upwardly on the pivot *d* to permit the insertion of spools *l* into the holes *b*.

Vertical slits *g*, tangentially arranged relative to the periphery of holes *b*, are provided in member *a* which connect the bottom face thereof with the holes *b*. These 100 105 110 115

slits *g*, clearly shown in Figs. 2 and 3, form a passageway for the threads *h* as they leave the spools *b*. Centrally arranged on the front face of the body *a* is a hook-shaped device *j* which bears a cutter *j'*, by means of which the threads *h* may be severed. The thread *k'* (see Fig. 2) is shown drawn up from the slit *g* over the hook member *j*. A slight pull on the free end of the thread *k'* will sever the same against the cutter *j'*. It is to be noted particularly that the member *e*, previously described, closes the open end of all the slits *g* and thus confines the threads *h* within the slotted openings *g*. Furthermore, the member *e* forms a smooth rounded guide for the threads. Thus when the thread *k'* is drawn up, as shown in Fig. 2, it is prevented from catching upon the edges of the slotted openings *g* by this bar *e*. Thus, I have provided a simple, inexpensive, yet convenient and efficient, means for holding a number of spools of thread. It is recognized that many changes and modifications may be made in the structure herein disclosed without departing from the scope of my invention which is more truly defined in the appended claims.

What I claim is—

1. A spool holder, comprising, a body member with a plurality of holes in one face thereof, adapted to receive spools of thread, said body member being formed with a plurality of slits, extending from said holes to another face of said body, whereby threads from said spools may be conducted from said body, a depending bar pivoted to said body and adapted when in one position to hold said spools within said body and when in another position to permit the insertion of said spools into said holes, and means to secure said bar in the first-named position.

2. A spool holder, comprising, a body member with a plurality of holes in one face thereof adapted to receive spools of thread, said body member being formed with a plurality of slits, tangentially arranged with respect to said holes and extending therefrom to another face of said body, whereby threads from said spool may

be conducted from said body, a depending bar pivoted to said body and adapted when in one position to hold said spools within said body and when in another position to permit the insertion of said spools into said holes, a second bar secured to said first-named bar, adapted to confine the threads in said slits, and means to secure both bars in the first-named position.

3. A spool holder, comprising, in combination, a body member with a plurality of holes in one face thereof, adapted to receive spools of thread, said body member being formed with a plurality of slits, tangentially arranged with respect to said holes and extending therefrom to another face of said body, whereby threads from said spools may be conducted from said body, a depending bar pivoted to said body and adapted when in one position to hold said spools within said body and when in another position to permit the insertion of said spools into said holes, a second bar secured to said first-named bar, adapted to confine the threads in said slits, means to secure both bars in the first-named position, and a cutter member secured to said body member.

4. A spool holder, comprising, a body member provided with a row of horizontally arranged holes leading from one face thereof adapted to receive spools of thread, and vertical slits one leading from each hole to the bottom and front face of the member through which the thread may pass from each spool, means constructed to partially close the open end of all of said holes to bind the spools therein and to close the front bottom end of all of said slits to insure the thread leaving the slits through the bottom openings, said means being arranged along the bottom front edge of the body member whereby the thread may be guided and slid therealong without catching in the slit openings.

JOSEPH H. SHEARN.
